UNITED STATES PATENT OFFICE.

CHARLES A. BURDICK, OF KENOSHA, WISCONSIN.

INK-BOTTLE ATTACHMENT.

1,343,960.

Specification of Letters Patent.

Patented June 22, 1920.

Application filed January 12, 1920. Serial No. 350,931.

To all whom it may concern:

Be it known that I, CHARLES A. BURDICK, a citizen of the United States, and resident of Kenosha, in the county of Kenosha and State of Wisconsin, have invented certain new and useful Improvements in Ink-Bottle Attachments; and I do hereby declare that the following is a full, clear, and exact description thereof.

10 My invention relates to attachments for ink bottles, but it also may be applied to other kinds of containers, and when used with the former is designed to form a combined stopper holder and pen rest.

15 One of the principal objects of the present invention is to provide a simply constructed and inexpensive attachment which can be snapped about the neck of an ink bottle in position to provide a handy receiver for the stopper when removed so that danger of soiling the table or the like on which the bottle is placed is obviated.

20 An additional object is to provide an ink bottle attachment having a stopper receiver and a pen rest so combined that they form a unitary article which can be easily attached or detached from an ink bottle. The attachment in addition to being used in connection with an ink bottle may also be used on other 25 varieties of containers, for instance on a mucilage bottle, in which case the stopper receiver will perform its usual function of holding the stopper when removed, while the pen rest may be used to receive the 30 mucilage brush.

35 With the foregoing and other objects in view, the invention consists in the novel features of construction, combination and arrangement of parts which will be herein-after more particularly described and claimed.

In the accompanying drawing:

40 The figure represents an ink bottle having my invention applied thereto, the same being shown supporting the bottle stopper and a pen.

45 Referring more particularly to this drawing, a conventional form of ink bottle is designated by the reference numeral 1, and this 50 bottle includes a cylindrical neck 2 having a bead or the like 3 surrounding its mouth which is normally closed by a stopper 4. The invention is particularly adapted to support the stopper so as to eliminate the 55 necessity for placing it upon the table T when the bottle is open. A pen P is like-

wise prevented from soiling the table by a rest which is a part of the invention.

The attachment of which the stopper receiver and the pen rest form the major parts 60 consists of a single piece of resilient wire bent to form a pair of resilient or spring arms 5, a stopper receiving socket 6 and a substantially V-shaped spring member 7, the apex portion of which is bent into hook-shape as at 8 to provide said pen rest. The stopper receiving socket 6 is formed of a ring or loop of resilient wire and has the pair of spring arms 5 rigidly connected therewith as at 9. The stopper receiving 70 socket 6 and these resilient arms 5 are thus substantially in the same horizontal plane.

The arms 7' of the spring member 7 are connected with and merge into the corresponding arms 5, but are inclined downwardly from the plane of the arms 5 to one side of the bottle 1. The hook-shaped end 8 of the member 7 thus projects laterally. However, the provision of the spring member, the same being substantially V-shaped, 80 connected with the arms 5 adds a greater spring tension or resiliency thereto to permit the attachment to more effectively embrace the bottle neck. This is obviously caused by the shape of the member 7. 85

In applying the attachment to the bottle 1, one of the arms 5 is first placed under the bead 3 and then the other arm is forced down over the portion of the bead opposite that beneath which the first arm is placed, 90 thereupon the arms 5 spring toward each other and snap about the bottle neck. In removing the device a reverse procedure may be employed, or the end 8 of the member 7 may be raised upwardly thus spreading the 95 portions of the arms 5 which merge into the arms 7', the diameter of the neck embracing portion of the attachment thereby being increased to facilitate its ready removal. Inasmuch as the attachment is preferably 100 formed from but a single piece of wire, the ends of the same are brought together and coiled about the intermediate portions as at 9. A very simple and inexpensive article is thus formed and one which would be thoroughly efficient in operation and use. 105

Attention is directed to the fact that simplicity of the device is increased by having the stopper receiving socket rigidly connected with the other part so that it is 110 always in a position to receive the stopper when the same is lifted from the mouth of

the bottle. Likewise it is to be noted that the member 7 is of such a length that the rest 8 will be quite close to the table to thereby overcome any likelihood of the pen P from 5 sliding from the rest and on to the table as would be the case if said rest were higher.

I claim:

1. A stopper holder for containers comprising a stopper receiving seat, a pair of 10 resilient arms extended from the seat and adapted to spring around a container, and a substantially V-shaped spring member having the ends of its arms connected with the corresponding resilient arms whereby to increase the spring tension of the latter.
- 15 2. A stopper holder for containers com-

prising a stopper receiving seat, a pair of resilient arms extended from the seat and adapted to spring around a container, and a substantially V-shaped spring member having 20 the ends of its arms connected with the corresponding resilient arms whereby to increase the spring tension of the latter, the main portion of said member being extended downwardly, its lower free end being bent 25 laterally to provide a substantially hook-shaped article rest.

In testimony that I claim the foregoing I have hereunto set my hand at Kenosha in the county of Kenosha and State of Wisconsin.

CHARLES A. BURDICK.
